UNITED STATES PATENT OFFICE.

FRANK C. ANDERSON, OF CINCINNATI, OHIO, ASSIGNOR OF SEVEN-TWENTIETHS TO GEORGE W. ZAPF, OF SAME PLACE.

INTERLOCKING JOINT FOR RAILWAY-RAILS.

SPECIFICATION forming part of Letters Patent No. 665,160, dated January 1, 1901.

Application filed July 27, 1900. Serial No. 25,026. (No model.)

To all whom it may concern:

Be it known that I, FRANK C. ANDERSON, a citizen of the United States, residing at Cincinnati, in the county of Hamilton and State 5 of Ohio, have invented certain new and useful Improvements in Interlocking Joints for Railway-Rails, of which the following is a full, clear, and exact description, reference being had to the accompanying drawings, 10 forming part of this specification.

My invention relates to improvements in interlocked joints for the meeting ends of railway-rails, whereby the rail is held absolutely tight and is prevented from working 15 loose at the joint and is rendered stronger than it is at any other point in the track and also whereby it is rendered extremely difficult for a train-wrecker to disconnect the rails at the joint, the whole forming a simple, cheap, and 20 efficient joint tending greatly to increase the safety of travel and permit high speeds.

The novelty of my invention will be hereinafter more fully set forth, and specifically pointed out in the claims.

25 In the accompanying drawings, Figure 1 is a sectional end view through a rail and my improved interlocking joint applied thereto. Fig. 2 is a perspective view of the chair or bed piece which contains the ends of the rails 30 at the joints. Fig. 3 is a perspective view of one of the filling tie-plates. Fig. 4 is an enlarged elevation of one of the divided keys or pins. Fig. 5 is a side elevation of one end of one of the filling-plates, showing the location 35 of the key or pin in one of the elongated openings.

The same letters of reference are used to indicate identical parts in all the figures.

Referring to Fig. 1, A represents an ordinary T-rail of the usual or any suitable construction, of which a is the vertical web, b the double flange or foot, and c the head or tread-piece. Through the web of each rail, near its ends, are the usual perforations, 45 either round, oblong, or any other shape in cross-section for the passage of the fastening pins or keys B, by means of which two filling tie-plates C after the manner of fish-plates are secured one on each side of the web 50 a. These filling tie-plates, as seen in Figs. 1 and 3, are composed of a vertical web c',

whose lower edges are beveled to fit flush upon the flanges of the footpiece b and whose upper edges are beveled to fit under the under side of the head of the rail, and in addition they have outwardly-extended portions with undercut beveled lower edges, as seen at c².

When the ends of two rails are brought together, the filling tie-pieces are placed on each side, so as to overlap the joint after the manner of fish-plates, and elongated perforations h, through the webs of the tie-plates, are caused to register with the perforations in the web of the rail. Pins B, Fig. 4, having flaring lower portions g at their outer ends, 60 are then passed through the perforations h in the tie-plates and the perforations in the web of the rail, the pins being made small enough for this purpose, and then keys e are driven 65 in on top of the pins B to lock the latter in place, the flaring ends g occupying depressions i, Fig. 3, in the outer edges of the perforations h. A chair-piece D in the form of a partial sleeve with a flattened bottom portion to fit over and snugly embrace the foot 70 of the rail and which has been previously slipped over the end of one of the rails past the joint, is now slipped back and is driven over the webs of the filling tie-plates and over 75 the ends of the keys or pins B, thus completely covering the latter. The upper edges of the upturned ends of the sleeve D are beveled to fit under and engage the undercut edges c² of the tie-plates, thus forming a complete interlocking of all the parts.

Portions, as at d', Fig. 2, are cut in the edges of the flanged parts of the sleeve D to expose the edges of the foot of the rail and to receive the heads of the spikes by which the 90 rail is fastened to the ties in the ordinary manner. By this latter construction also the heads of the spikes are confined in recesses and prevent the endwise slipping of the chair-piece or sleeve D.

95 While I prefer that the filling-pieces C should have the outer projecting portions to engage the top edges of the chair-piece or sleeve, my invention is not to be limited to this construction, and a great part of its advantage would be obtained if the filling-pieces 100 were simply flat and extended between the

foot of the rail and the underside of the head, and in the latter case it would be desirable to extend up the vertical parts of the chair-piece or sleeve until they rested directly under the head of the rail. Again, while I have shown the locking-pins as round in cross-section to fit round perforations in the web of the rail, it is to be understood that this shape is not material and that the perforations in the web of the rail may be rectangular and oblong or of any shape desired, the pins being given a corresponding shape in cross-section. By means of the elongation of the perforations *h* in the tie-pieces the rails may expand or contract longitudinally without buckling or curving, and at the same time they will be held firmly and rigidly at their joints to the cross-ties, and a complete interlocking of the parts at the joints is thus effected.

Having thus fully described my invention, I claim—

1. An interlocking joint for the ends of railway-rails comprising a chair-piece or sleeve fitted over and embracing the flanges of the foot of the rail and filling tie-pieces uniting the webs of two adjacent rails by means of

pins passed through perforations in said tie-pieces and the webs of the rails, said filling-pieces being embraced by and held between the upright portions of the chair-piece whose upright portions cover and conceal the ends of the pins, substantially as described.

2. The herein-described interlocking joint for the ends of railway-rails, composed of the chair-piece D adapted to slip over and engage the flanges of the foot of the rails and having vertical portions extending up on each side and at some distance from the web of the rails, filling tie-pieces C united to the webs of the rails by means of pins B passed through elongated perforations in said tie-pieces and registering perforations in the webs of the rails, said tie-pieces extending between the foot of the rails and the undersides of the heads and having outward extensions with dovetailed portions to interlock with the upper edges of the vertical portions of the chair-piece, substantially as described.
